United States Patent Office

Des. 220,519

Patented Apr. 20, 1971

220,519

PLATE OR THE LIKE

Cynthia S. Gerow, Syracuse, N.Y., assignor to Corning Glass Works, Corning, N.Y.

Filed May 12, 1970, Ser. No. 22,934

Term of patent 14 years

Int. Cl. D7—01

U.S. Cl. D44—15

The figure is a top plan view of a plate of conventional configuration showing my new design.

I claim:

The ornamental design for a plate or the like, as shown and described.
